U.S. Patent Office

UNITED STATES PATENT OFFICE

THOMAS E. MURRAY, JR., OF BROOKLYN, NEW YORK, ASSIGNOR TO MURRAY
RADIATOR CORPORATION, A CORPORATION OF NEW YORK

RADIATOR

Application filed March 11, 1929. Serial No. 345,985.

The invention aims to provide certain improvements in radiators and similar apparatus which facilitates production and makes a better radiator.

5 The invention is particularly designed as an improvement upon the type of radiator shown in my previous application 310,959 filed October 8, 1928.

10 The accompanying drawings illustrate an embodiment of the invention.

Figs. 1 and 2 are respectively a plan and a side elevation of a radiator;

Fig. 3 is a horizontal section and Fig. 4 a vertical section illustrating one of the joints;

15 Fig. 5 is a perspective view of part of one of the corrugated sheets.

The heating element is a tube 1 for conveying steam or other heating medium, preferably made of thin copper for high conductivity. Applied to one or, preferably, to both of the opposite sides of the pipe are extended area structures, preferably also of thin sheet copper, corrugated in the manner shown. The extended area structure at 20 each side may be made of a single sheet extending the length of the radiator or of two or more sections making up the total length. Apparatus of this sort can be used not only as ordinary radiators for heating the air of 25 a room, but also for cooling the air by passing a cooling medium through the tube and for heat interchangers in other arts.

It is desirable to make the corrugated sheets of considerable extent so as to provide 30 an extended area for transmitting the heat to the surrounding air. It is also desirable to limit the width of the radiator so as to economize space required for its installation.

40 I accomplish these purposes by the special formation of the corrugated sheets. Each sheet is bent to provide the longitudinally extending portions 2 between which are major corrugations formed by transverse plates 3. 45 Thus we have vertical flues or passages which are alternately closed at the outside and open at the outside which cause a strong induced draft of the heated air so that it not only absorbs heat but is carried upward at an accelerating speed and circulated with compar-

ative rapidity throughout the room to be heated.

Each of the major corrugations referred to is provided with a deep groove in its outer wall, the sides 4 of which extend to or nearly to the tube 1 and thus divide the space into two smaller vertical flues which are closed at the outside and one of which is open. Instead of a single inward groove two or more such grooves may be formed in the major 55 corrugation between each pair of longitudinal plates 2, and the shapes of such grooves in cross-section may be varied from that shown. By this arrangement the cross-section of the extended area surface is divided into a number of comparatively small 60 passages between each pair of longitudinal plates 2 or points of attachment to the tube. 65

The attachment of the corrugated plates to the tube may be effected in various ways. 70 In the case illustrated, the longitudinal plates 2 are pressed out to form recessed portions 5 which embrace the pipe 1 and are preferably deep enough to bring the opposite plates 2 together as shown in Fig. 4. 75

Also the plates are punched with openings 6 which will lie immediately above and below the pipe. In Fig. 5 the plates 4 forming the secondary corrugations are shown of less width compared to the plates 3 than in 80 Fig. 1; the proportion may be varied, but it will be understood that the best practice is to make the sheets of final shape before applying them to the pipe.

The plates 2 are clamped together about the 85 pipe by means of straps having end portions 7 and recessed portions 8 which embrace the recessed portions 5 of the corrugated sheets. The opposite straps 7 are then united by welds 9 passing through the openings in 90 the sheets 2.

The space between two of the fins or transverse plates 3 at opposite edges of a longitudinal plate 2 is left open sufficiently for the easy insertion of the welding tools, and 95 the plates 2 are broad enough to secure a fairly wide contact with the pipe and to permit the making of a strong joint. Efficiency in operation of the radiator is secured by providing numerous transverse plates 3 and 4 100

close together and by providing a plurality of corrugations between the successive points of attachment to the pipe. This also results in narrow faces 10 exposed at the outer sides of the structure so that such faces are comparatively stiff and better adapted to resist accidental deformation than flat or widely rounded faces. This is important because the metal is thin and easily deformed by an accidental blow. Also the character of the corrugation serves to secure increased stiffness of the structure compared with a smaller number of wider corrugations.

Altho I have specifically mentioned cop-
15 per any of the common metals may be em-
ployed for either the tube or the sheets.
Among such metals are aluminum, brass, zinc,
iron or steel, etc.

Various modifications may be made by
20 those skilled in the art without departing
from the invention as defined in the follow-
ing claims:

1. A radiator including in combination a
heating element and an extended area struc-
25 ture united thereto consisting of thin sheet
metal having in horizontal section major
corrugations of which the inner portions are
attached at intervals to the heating element
and having a plurality of deep minor corrugations
30 between the points of attachment to
the heating element.

2. A radiator including in combination a
heating element and an extended area struc-
35 ture united thereto consisting of thin sheet
metal having in horizontal section major
corrugations of which the inner portions are
attached at intervals to the heating element
and having a plurality of minor corruga-
40 tions each extending inwardly substantially
or approximately to the side of the heating
element.

3. A radiator including in combination a
heating element and an extended area struc-
45 ture united thereto consisting of thin sheet
metal having in horizontal section major
corrugations which form inner longitudinal
plates engaging the heating element, trans-
verse plates extending outward from the
50 edges of each longitudinal plate with a space
between them equal in width at least to the
width of the inner, longitudinal plate, and
outer portions with a plurality of deep cor-
rugations between successive longitudinal
55 plates.

4. A radiator including in combination a
heating element and an extended area struc-
60 ture united thereto consisting of a thin metal
sheet corrugated in horizontal section to pro-
vide longitudinal plates engaging the heating
element, transverse plates extending out-
wardly from the edges of each longitudinal
65 plate with a space between them equal in
width at least to the width of the longitu-
dinal plate, and with a plurality of corru-
gations extending inwardly substantially or

approximately to the side of the heating ele-
ment between successive longitudinal plates.

5. A radiator including in combination a
long narrow horizontal heating element and
an extended area structure united thereto
70 consisting of thin sheet metal having in hor-
izontal section major corrugations of which
the inner portions are recessed to embrace
the heating element and provide a heat con-
ducting path of large area, and having also
75 a plurality of deep minor corrugations be-
tween the points of application to the heat-
ing element.

In witness whereof, I have hereunto signed
my name.
